UNITED STATES PATENT OFFICE.

ALBERT KRAUTH, OF HAMILTON, OHIO.

PAPER FEEDING, SEVERING, AND STORAGE APPARATUS.

1,098,511.

Specification of Letters Patent.

Patented June 2, 1914.

Application filed June 21, 1913. Serial No. 774,975.

To all whom it may concern:

Be it known that I, ALBERT KRAUTH, a citizen of the United States, residing at Hamilton, in the county of Butler and State 5 of Ohio, have invented certain new and useful Improvements in Paper Feeding, Severing, and Storage Apparatus, of which the following is a specification.

My invention relates to an improvement 10 in manifolding devices or autographic registers, and in a type of machine having a measured stroke or stop limitation after a definite prescribed feed of paper, so as to issue from the machine, and also file or 15 compile within the machine invariable constant lengths of paper which are severed from the continuous advancing sheets. The lengths discharged or issued from the machine are deposited upon a receiving tray, while those 20 deposited within the machine are consecutively compiled one above the other upon a removable tray.

The feeding mechanism comprises a well known type, in the nature of a pair of coacting rolls geared together. A master gear 25 is provided and herein preferably of segmental form in which the toothed contour is of a circumferential length equal to a prescribed length of paper feed desired for each 30 revolution of the master gear, with the non-toothed contour of the gear, providing an idle interval for the feeding rolls, to discontinue the feed of the paper.

The paper severing mechanisms are connected with the transmitting elements of the 35 master gear so that a paper feeding and paper severing operation is had to each revolution of the gear controlling the operating interval of the paper feeding rolls. Such 40 operation also positions the stored length so that it can be properly compiled when severed from the continuous sheet. The various steps required to perform the desired functions, are accomplished in one revolution or 45 an operative cycle of a manipulating crank handle, insuring the delivery of constant invariable lengths of paper in plural numbers for various purposes.

An object therefore of my invention is to 50 provide a rotative paper severing member having plural numbers of cutting edges adapted to be successively brought into operation with a coacting cutter member at timed intervals, relatively successively, to 55 an interval of operation of the paper feeding mechanism in which the rotative ele-

ments, of both the paper feeding mechanism and paper severing mechanism, are positively operated in their functioning direction.

60

Another object of my invention is to provide means for depositing a severed length of paper upon or within a receiver and provide means for forcibly directing such stored length upon the receiver, together with 65 means for alining the same upon the receiver, so that a series can be compiled in sequence, one upon another.

Other objects will be in part obvious from 70 the annexed drawings, and in part indicated in connection therewith by the following analysis of this invention.

This invention accordingly consists in the features of construction, combination of the parts and arrangements of elements deducible herefrom, and in the unique relations 75 of the members all as more completely outlined herein.

To enable others skilled in the art so fully to comprehend the underlying features 80 thereof that they may embody the same by numerous modifications in structure, relation, steps and sequence thereof contemplated by this invention, drawings depicting a preferred form have been annexed as 85 a part of this disclosure, and in such drawings, like characters of reference denote corresponding parts throughout all the views, of which:—

Figure 1 is a side elevation of my apparatus 90 with some of the cover plates of the propelling mechanism removed, and a portion shown in section for clearer observation of certain details of construction. Fig. 2 is a central vertical section through the 95 same. Fig. 3 is a side elevation opposite from that shown in Fig. 1, with a cover plate removed. Fig. 4 is a perspective view of the rotative cutter member. Fig. 5 is a detail top plan view of the compiling arm.

100

The construction of some of the components of the machine are of the well known type in this class of apparatus, and although essential, may be variously modified, or different types employed, and as to such general features no elaborate description will be made as to their specific form of construction. Only such reference will be made thereto as is sufficiently comprehensive for a clear understanding in this invention.

105

The machine is provided with a base 1, upon which the side frames 2, 3, are secured,

110

forming a casing for the apparatus. The side frames may each be of separable form, one member hingedly mounted upon a second for more convenient access to the interior of the casing. Within the interior of the casing or side frames a series of web supporting journals are provided for rotatively supporting the supply webs of paper. These journals may be of any type of construction, but as illustrated each comprises a pair of angularly disposed elastic arms, each having a cup disk secured at its free end, with the cup adapted to engage into the core of the web, and its flange engaging the side of the web exerting the spring tension thereon for the proper unwinding of the roll. Above the supply webs of paper, and between the side frames a writing-table 5 is mounted, over which the ends of the paper pass toward the paper feeding rolls 6, 7.

8, 9, and 10 represent guide rolls journaled in rear of the writing-table, one guide roll being provided for each web of paper 25 mounted within the machine. These rolls as shown are journaled upon a swinging frame 11, movable therewith so as to provide clearance or accessibility to the interior of the casing for web insertion or removal. 30 12 represents a margin-frame supported upon the side frames 2 and 3, and over the writing-table which serves as a top or cover for the casing. The casing may be provided with end doors mounted, as is customary in this class of machine, arranged to prevent unauthorized access to the interior of the machine and especially to the storage compartment at the forward part of the machine, housing the record slips.

40 *Paper feeding mechanism.*—The paper feeding mechanism herein employed, as heretofore stated, comprises a well known type consisting of a pair of coating rolls as the most preferable, but their disclosure herein, should not be limited to the term "feeding mechanism" of the claims herein, unless particular reference is made thereto. The roll 7 is journaled in fixed bearings, while the roll 6 is journaled in slide-blocks 50 mounted in each of the side frames, each having a spring engaging against the same to force the roll downwardly into engagement with roll 7, to frictionally engage the paper fed between the rolls. At one end 55 of the upper roll 6 a gear 13 is fixed, intermeshing with a gear 14, fixed to the axis of the lower roll 7. 15 represents a second gear fixed to the axle of roll 6 mounted preferably within a recess of the frame 3; said gear is adapted to intermesh with the toothed portion of the segmental master gear 16 fixed to the shaft 17 and journaled in the side frames, see Fig. 3. The segmental master gear 16 has a toothed contour with a circumference at the pitch di-

ameter of the teeth, equal to the length of paper advance desired for each revolution of the master gear, and a non-toothed contour providing a non-transmitting interval in the revolution of said gear, or a dormant period of the feeding rolls, during the operation of the paper severing mechanism, so as not to advance the paper while it is being severed. Fixed to the shaft 17 is a crank handle 18 for revolving the shaft, which handle may be limited in its rotation, so as to be arrested after a prescribed paper feeding operation, with provision made for manual release for each successive operation, or a crank handle may be free for continuous rotation wherein the accuracy of the issued lengths is not material.

85 *Paper severing mechanism.*—The paper severing mechanism comprises a rotative cutter member 19, journaled in fixed bearings in the side frames. It is provided with two cutting edges 20, 21, adapted to successively engage with the cutting edge of a relatively stationary cutting member 22, 90 slidably mounted within the side frames and urged toward the axis of the revolving cutter member. A spring is provided for each end of the knife mounted within the respective side frames, (see Fig. 1). The stationary cutting member preferably has 95 its cutting edge disposed longitudinally parallel with the axis of the revolving cutter member. The cutting edges of the revolving cutter member are preferably spiral longitudinal so as to progressively engage 100 with the cutting edge of the stationary cutter to produce a shear action in a direction toward the paper feed rolls. The upper surface of the stationary cutter member 22, intermediate of its ends is preferably angled, 105 to guide the paper upwardly in its discharge from the machine to be deposited upon the tray plate 23 mounted between the side frames. The tray 23 also serves as a cover for the storage compartment. It may be 110 arranged to be readily removable or permanently fixed to the side frames. It is also desirable to support the tray in a recessed position relative to the edges of the side frames so as to provide a guide for the paper in its travel on the tray.

115 The rotating cutter member is arranged to come to rest in a position with its cutting edges away from the stationary cutting member to provide a clearance between the 120 same so as not to interfere with the free travel of a successive length of paper which must be fed between the cutter members. It is desirable to discontinue its rotation during a paper advancing interval, and, therefore, I provide a segmental pinion 24, (see Fig. 1), upon the shaft 17 capable in its rotation to intermesh with pinion 25, fixed to the axis of the rotative cutter member 19, imparting a half revolution to said cutter 125 130

member upon each complete rotation of the crank handle and the position of the gearing is such as to render its power transmission effective during the dormant period of the feeding rolls after the teeth of the master gear 16 are free from engagement with a roll gear 15.

While I have shown two cutting edges upon the rotative cutter member, it is obvious, however, that the number can be changed without departing from the principles and features of this invention.

To prevent the stationary cutter member from moving beyond the circumferential cutting edges of the rotary cutter member, I provide said rotary cutter member 19 with annular flanges 23^a, one at each end thereof, as illustrated in Fig. 4, against which the stationary cutter member engages; to limit its movement toward the axis of the rotary cutter member. This always insures the proper co-operation between the two cutting members and prevents their overlapping, which would destroy or injure their edges.

Record storage.—Within the casing and in front of the feeding and severing mechanism I provide a compartment for receiving the record lengths of papers. The lengths are sequentially compiled, one upon another consecutively as issued. This offers convenience in examining the record lengths, presenting the same substantially in book form and obviates the difficulty heretofore experienced in record manifolding devices wherein the record strip was rewebbed within the machine. Such rewebbing necessitating the unwinding of the entire web, in some instances when reference was desired to a particular entry. As the record strip is advanced within the machine it is fed over a removable tray 26, and when severed from the continued strip it is deposited thereon. The tray 26 is arranged so that it can be removed from the machine or slid outwardly for convenient access to the stored lengths in removing the same from the machine.

To forcibly depress the stored lengths upon each other and insure the same to be consecutively distributed, one upon the other, I provide an elastic oscillating arm 27 in the nature of a wire bent in U-form with its ends hingedly connected to the rock shaft 28. The free end of the arm extends toward the feeding mechanism so as to insure depression of the rear end of the record length to clear the same for a succeeding advancing length. This arm has a spring 30 engaged therewith and fixed to the rock shaft 28 so as to render the same yielding to accommodate itself to the increasing height of the stored lengths without interfering with the operation of the oscillating mechanism.

The arm 27 is oscillated or moved downwardly toward the tray 26 by the following

mechanism: 31 represents a cam wheel fixed upon the shaft 17 as illustrated in dotted lines, Fig. 3, having a cam element 32, projecting therefrom, adapted to engage the connecting rod 29 to reciprocate the same. 70 The connecting rod 29 is connected to the crank arm 33 fixed to the rock shaft. Thus upon each rotation of the cam wheel 31, at a proper interval the arm 27 will be depressed toward the tray 26 successively of a 75 paper severing operation.

The mechanism is normalized by a spring 34, fixed to the rock shaft 28 and frame of machine, as illustrated in Fig. 5. After a length has been deposited on the machine it 80 is alined upon the tray, one edge thereof with a relative edge of the tray to present the same in a uniform compiled position, so that the lengths may be conveniently secured together by fastening devices. This 85 alined mechanism comprises an angle plate 35, having one limb thereof slidably mounted beneath the tray 26, with its second limb at right angles thereto for engaging the edge of the paper. 90

36 represents a rock shaft, see Fig. 2, journaled within the side frames, provided with an arm 37 fixed thereto, its free end being slotted to receive a pin 38, fixed in the lug 39, projecting from the angle plate 35. The 95 rock shaft 36 is provided with a second arm 40, adapted to engage a cam element 41 of the cam wheel 42, fixed on the shaft 17, as illustrated in Fig. 3. Thus in the rotation of the shaft 17, the master or segmental gears and cam wheel relatively fixed thereon will operate their respective elements at relative timed intervals in each revolution of the shaft 17, first to feed the paper, second, to sever the length from the continuous sheet, 100 third, to depress the same upon the storage tray or receiver and to aline the lengths thereon. 105

The gearing and relative movements of the operative elements may be variously 110 modified and the number of revolutions of the crank handle to an operating cycle for a prescribed length of paper feed varied from the single rotation type herein illustrated, within the province of this invention, and 115 without further elaboration, it is regarded that the foregoing would reveal the gist of this invention that others can, by current knowledge, readily adapt for various applications without omitting certain features 120 that, from the standpoint of the prior art, fairly constitute the characteristics of the generic or specific aspect of this invention, and, therefore, such adaptations should be comprehended in the range of equivalents 125 of the following claims.

Having thus revealed my invention, I claim as new and desire to secure by Letters Patent of the United States:—

1. A device of the nature disclosed com- 130

bining paper feeding mechanism, paper severing mechanism for severing the paper after each predetermined length of feed, and mechanism for sequentially compiling the severed lengths, comprising a receiving tray, a yielding arm positively oscillated subsequent to each paper severing operation to depress an advancing length upon the tray, and a reciprocating member movable 10 to engage the edge of a severed length and aline the same with a relative edge of said receiving tray.

2. A device of the nature disclosed combining paper feeding mechanism operated in 15 predetermined cycles for feeding a continuous web of paper to serially advance in variable constant lengths thereof, and paper severing mechanism operated successively to each paper length advance to sever the same 20 from the web, comprising a non-rotative cutter member, a rotative cutter member provided with a plural number of cutting edges sequentially moved tangent to the cutting edge of said non-rotative cutter member in a 25 direction opposed to the feed of the paper, said rotative cutter member at each end provided with an annular flange engaged with said non-rotative cutter member, and means for yieldingly urging said non-rotative cutter member toward the axis of said rotative cutter member.

3. A device of the nature disclosed combining a pair of coacting paper feeding rolls, coacting paper severing members, comprising 35 a rotative cutter member provided with a plural number of cutting edges with the ends of said cutter member annularly and yieldingly engaged with a non-rotative cutter member, and a non-rotative cutter member, propelling mechanism for said paper feeding rolls and rotative cutter member, and means intervening said paper feeding rolls and rotative cutter member for intermittently rotating said cutter member successive 40 of a paper feeding interval for cooperatively engaging one of the cutting edges of said rotative cutter member with said non-rotative cutter member.

4. A device of the nature disclosed combining a pair of coacting paper feeding rolls, coacting paper severing members, comprising a rotative cutter member having a plural number of cutting edges, and provided at each end with an annulus, each adapted to 50 peripherally engage with a non-rotative cutter member, a non-rotative cutter member, propelling mechanism for rotating said rolls to advance a predetermined length of paper and successively thereafter rotate said cutter member to bring into coöperation one of the cutting edges of said rotative cutter member with said non-rotative cutter member to sever the predetermined length of paper from its continuous web.

5. A device of the nature disclosed com-

bining a pair of coacting rolls yieldingly urged toward each other and positively rotated in opposing directions, a master gear for rotating said rolls having a toothed contour of a circumferential length at its tooth pitch diameter equal to a predetermined length of paper advance for each revolution of said gear with the remainder of its contour non-toothed, capable of providing an active and inactive interval for said rolls in each cycle of operation of said master gear, a rotary cutter member having a plural number of cutting edges, each longitudinally spiral, and a relatively stationary cutter member yieldingly urged toward the axis of said rotary cutter member, a segmental gear for rotating said cutter member intermittently relative during the inactive interval of said master gear to coöperatively engage one of the cutting edges of said rotary cutter member with said stationary cutter member and normalizing at relative different planes, and propelling means for rotating said gears.

6. A device of the nature disclosed combining paper feeding mechanism operated in predetermined cycles for feeding a continuous web of paper to serially advance in variable constant lengths thereof, and paper severing mechanism operated successively to each paper length advance to sever the same from the web, comprising a relatively stationary cutter member, a rotary cutter member provided with a plural number of cutting edges sequentially moved tangent to the cutting edge of said stationary cutter member in a direction opposed to the feed of the paper, and means for yieldingly engaging said stationary cutter member toward the axis of said rotary cutter member, a storage element to receive an advancing length of paper, and means operated in time movements relative with the feed and severance of the paper to sequentially compile the lengths upon said storage element.

7. A device of the nature disclosed combining paper feeding mechanism operated in predetermined cycles for feeding a continuous web of paper to serially advance in variable constant lengths thereof, and paper severing mechanism operated successively to each paper length advance to sever the same from the web, comprising a relatively stationary cutter member, a rotary cutter member provided with a plural number of cutting edges sequentially moved tangent to the cutting edge of said stationary cutter member in a direction opposed to the feed of the paper and means for yieldingly engaging said stationary cutter member toward the axis of said rotary cutting member, and means for alining one edge of said compiling lengths.

8. A device of the nature disclosed combining a pair of coacting paper feeding

rolls, coacting paper severing members, comprising a rotative cutter member having a plural number of cutting edges and a relatively stationary cutter member, propelling a mechanism for said paper feeding rolls and rotative cutter member, and means intervening said paper feeding rolls and rotative cutter member for intermittently rotating said cutter member successive of a paper feeding interval for coöperatively engaging one of the cutting edges of said rotary cutter member with said stationary cutter member, and a storage element to receive an advancing length of paper in sequential compilation.

9. A device of the nature disclosed combining paper feeding mechanism, paper severing mechanism for severing the paper relatively after a predetermined length of paper feed, and mechanism for sequentially compiling the severed lengths, comprising a movable base member, a yielding arm oscillated subsequently to each paper severing operation to depress an advanced length upon said base member, and a reciprocating member movable to engage the edge of the advancing length and aline the same with a relative edge of said base member.

10. A device of the nature disclosed combining paper feeding mechanism, paper

severing mechanism for severing the paper beyond the feeding mechanism after a predetermined feed thereof, and mechanism for sequentially compiling the several lengths within a storage compartment, comprising a yielding arm oscillated subsequently to each paper severing operation to depress an advanced length upon the base of said compartment, and alining means for the paper lengths deposited.

11. A device of the nature disclosed combining paper feeding mechanism, paper severing mechanism for severing the paper after each predetermined length of paper feed, and mechanism for sequentially compiling the severed lengths comprising a receiving tray, a yielding arm oscillated subsequently to each paper severing operation to depress an advanced length upon the tray, and alining means therefor comprising an angle plate having one limb disposed at right angles to said tray and adjacent one edge thereof, a lever engaged with said angle plate, and means for oscillating said lever.

In testimony whereof, I have hereunto set my hand.

ALBERT KRAUTH.
